VALVE RESEATING TOOL

Filed Dec. 16, 1927

UNITED STATES PATENT OFFICE

ROY A. STOUGAARD, OF DETROIT, MICHIGAN, ASSIGNOR TO PACKARD MOTOR CAR COMPANY, OF DETROIT, MICHIGAN, A CORPORATION OF MICHIGAN

VALVE RESEATING TOOL

Application filed December 16, 1927. Serial No. 240,359.

This invention relates to devices for grinding valve seats.

In the manufacture of cylinder blocks the cylinders together with their respective valve ports are cast in block. Guide holes are drilled and reamed normal to the top face of the block and guides are then pressed in and accurately reamed for the reception of valve stems. A cutting tool is mounted for rotation on a mandrel which snugly fits the valve stem guide to cut the valve seat concentric and normal to the valve stem guide, thus when the valve is installed it fits the seat perfectly. The cylinder block and valve stem guide are cast iron which is subjected to seasoning when heated, and during the seasoning the texture of the metal changes. This sometimes causes the valve seats to warp but more often the valve stem guide will warp and change its position slightly, so that it is no longer in proper alignment with the valve seat. In order to correct these evils, the valve should be reseated by making the seat concentric and normal to the new position of the guide, and it is the aim of the present invention to provide a device for this purpose.

An object of the invention is to provide a device for cutting valve seats concentric and normal to the axis of the valve stem guide.

Another object of the invention is to provide a device for cutting valve seats which can be easily and quickly adjusted and will efficiently perform its intended function.

Another object of the invention is to provide a device for cutting and finishing a valve seat which can be quickly centered in a valve stem guide and so supported for operation that it will maintain its alignment.

Still a further object of the invention is to provide a device for cutting valve seats which has the advantage of a positive action in cutting valve seats concentric and normal to the valve stem guides, a device which is highly efficient in operation, yet of marked simplicity as a whole and in respect to each of its component parts, so that its manufacture is economically facilitated both as regards to parts and their assembly.

Other objects of the invention will appear

from the following description taken in connection with the drawings which form a part of this specification, and in which:

Fig. 1 is a perspective view illustrating the invention in an operative position on a cylinder block of an internal combustion engine, a portion of the cylinder block being broken away.

Fig. 2 is a view taken substantially on line 2-2 of Fig. 1 with parts in section, and

Fig. 3 is a view taken substantially on line 3-3 of Fig. 2, the cylinder block being omitted.

Referring by numerals to the drawings, 10 represents the cylinder block of an internal combustion engine having a plurality of cylinders 11 together with inlet ports 12 and exhaust ports 13. The ports are provided with the usual valve seat 14 and have positioned therein valve stem guides 15. The cylinder block has threaded into its upper face a number of studs 16 for securing in position a cylinder head, not shown.

A tapered mandrel 17 having a cylindrical head 18 is fitted into the guide 15 and made secure by any suitable means, such as by a nut, not shown, threaded upon the lower end of the mandrel. A split sleeve or bushing 19 is fitted upon the head of the mandrel and secured in place by a lock nut 20. This sleeve provides a bearing for a cutting or finishing tool 21. As shown, the tool is a rose cutter of the usual type having its teeth ground to the proper angle to cut the valve seat face as indicated at 14. The cutting tool is centrally bored as indicated at 22 and is mounted to rotate freely on the bushing 19 and is provided in its upper face with recesses or sockets 23, the object of which will herein-after appear.

Positioned upon the face of the cylinder block is a support having a base 24 provided with a slot 25 for the reception of the stud bolts 16 in the upper face of the cylinder block. As shown, the base is substantially semi-circular and is provided with an arm 26 inclined from the perpendicular and bifurcated at the base, as indicated at 27, to permit the insertion of a wrench 28. The wrench has a handle 29 for the manipulation thereof

and an enlarged portion 30 internally threaded to receive the threads on the stud bolts 16 by means of which the base is clamped in position. The upper or free end of the arm 26 is provided with a boss 31 having a vertically disposed bore 32.

Mounted to reciprocate and to rotate in the bore 32 is a hollow shaft 33 having a handle 34 for the manipulation thereof, a coupling 35 and an adjustable sleeve or collar 36, the collar being adapted to bear upon the upper face of the boss 31 to limit the downward movement of the shaft, the object of which will hereinafter appear. The coupling 35 has a central bore 37 and a counter bore 38 formed to provide a socket for the reception of a head 39, the connection being in the nature of a universal joint, and a pin 40 is provided to prevent rotary movement between the parts. The head 39 is adapted to bear upon the upper face of the cutting tool 21 and is provided with a recess 41 for the reception of the head of the mandrel and pins 42 so positioned in its lower edge to engage the recesses 23 in the tool and thereby interlocking the head with the tool.

In operation the mandrel 17 is centered in the valve stem guide 15 and made secure. The cutter 21 is then placed upon the bushing 19 on the head of the mandrel. The cutter is fitted to rotate smoothly and is adapted to be driven by the shaft 33 which is supported in a vertical bore in the boss 31 on the free end of the arm 26. The arm 26 and its associated parts will take any stress exerted on the shaft 33 by reason of carelessness on the part of a mechanic, so that such stresses will not be communicated to either the mandrel or the cutting tool. The arm 26 is integral with the base 24 and the base is made adjustable on the upper face of the cylinder block; so that the shaft may be supported substantially in alinement with the cutting tool. In order to rectify any variations in the alinement of the shaft with the cutting tool, due to adjustment of the arm on the cylinder block or to the changed position of the valve guide, the head 39 carried by the shaft 33 and engaging the cutting tool has a universal connection with the shaft which permits the cutting tool to maintain a position normal to the axis of the mandrel without strain on the mandrel. The shaft is rotated by hand and is provided with an adjustable collar, adapted to be locked in position by a thumb screw to limit the downward movement of the shaft. As the collar engages the upper face of the boss 31 the downward movement of the shaft is stopped and the cutting tool will cease to function. It is by this means that the depth of the cut may be regulated or adjusted perfectly.

While I have herein described in some detail a specific embodiment of my invention, which I deem to be new and advantageous

and may specifically claim, I do not desire it to be understood that my invention is limited to the exact details of the construction, as it will be apparent that changes may be made therein without departing from the spirit or scope of my invention.

Having thus described the various features of my invention, what I claim as new and desire to secure by Letters Patent is:

1. A device for cutting valve seats comprising a mandrel adapted to be positioned in a valve stem guide, a cutting tool rotatably mounted on the mandrel, a head having an interlocking connection with the cutting tool, a shaft having a handle for the rotation thereof, a flexible coupling between the shaft and the head, an arm supporting the shaft, a base for said arm, and means for adjusting and securing the same in a fixed position. 75

2. A device for cutting valve seats comprising a base, an arm supported thereby, a shaft supported by the arm, a mandrel adapted to be supported in a valve stem guide, a sleeve locked upon the mandrel, a cutting tool mounted for rotation on the sleeve, a head pivotally connected to the shaft and an interlocking connection between the head and the cutting tool. 85

3. A device for cutting valve seats comprising an adjustable base, an arm supported by the base, a boss on the free end of the arm having a perpendicular bore, a shaft mounted for rotation and reciprocation in the bore, an adjustable stop on the shaft, a mandrel adapted to be supported in a valve stem 95 guide, a bearing sleeve locked upon the mandrel, a cutting tool mounted for rotation on the bearing sleeve, a head flexibly connected to the shaft and an interlocking connection between the head and the cutting tool. 100

4. A device for cutting valve seats comprising a mandrel adapted to be supported in a valve stem guide, a bearing sleeve locked upon the mandrel, a cutting tool mounted for rotation on the bearing sleeve, a shaft supported for rotation in the bearing sleeve, a head loosely connected to the shaft for universal movement in a horizontal plane having a locking connection with the cutting tool and an arm supporting the shaft in alinement with the cutting tool. 110

In testimony whereof I affix my signature.

ROY A. STOUGAARD.
